ceased

Application December 29, 1931, Serial No. 583,717

4 Claims. (Cl. 262—20)

This invention relates to quarrying apparatus and has for its object the provision of a machine by which vertical channels in the stone may be cut along right lines and a number of slabs or blocks may be cut simultaneously from the bed with at least two finished faces. The invention has for an object the provision of a machine which will simultaneously cut stones of desired length at the sides of the machine and form a large block directly under the machine, and which machine will be held to a fixed path so that the stone-channeling elements will operate on straight lines and perform their work in the most efficient manner. The invention provides means whereby the operation of the channeling elements and the travel of the machine may be very easily and effectually controlled and the channeling elements caused to follow the channels as the cutting of the same progresses. It is also an object of the invention to provide means whereby stones may be separated from the bed of the quarry with a partly finished surface so that the stone, as taken from the quarry, will be practically ready to set, subsequent dressing being minimized and, in many instances, eliminated. Other incidental objects will appear in the course of the following description, and the invention resides in certain novel features which will be particularly pointed out in the appended claims.

30 In the accompanying drawings, illustrative of the invention,

Figure 1 is a perspective view of the stone-channeling machine as it appears when at work, several portions of some separated stones being shown in order that the operation may be more readily appreciated.

Fig. 2 is a side elevation of the machine on a larger scale.

Fig. 3 is a longitudinal vertical section through the machine,

Fig. 4 is a diagram illustrating an arrangement of cables which may be advantageously employed, at times, with the machine,

Fig. 5 is a horizontal section on the line 5—5 of Fig. 3,

Fig. 6 is a transverse section on the line 6—6 of Fig. 5,

Fig. 7 is an enlarged transverse section on the line 7—7 of Fig. 3,

Fig. 8 is a detail elevation,

Fig. 9 is a detail showing a variation.

In the drawings, the reference numeral 1 indicates a quarry bed from which stones are to be cut, and in Fig. 1 the reference numeral 2 indicates a block while the numeral 3 indicates slabs

of less width which have been formed by the operation of the machine constituting the present invention. The machine is illustrated as running upon a block 4, which is being divided, and it is mounted to travel on tracks 5 which are laid upon the surface of the block and anchored thereto. As shown most clearly in Fig. 7, the tracks 5 comprise rails of the usual T-section which are set upon ties 6 and are connected by struts or braces 7 whereby the parallel relation of the rails will be maintained, the ties resting upon mating wedge-shaped shims 8 whereby the track may be leveled and a firm support for the same upon the quarry bed established. The shims 8 may also be provided at such points in the lengths of the rails as may be deemed advantageous and may be interposed directly between the bed block and the rails. The track is anchored, at intervals, by bolts 9 which have their lower ends engaged in plugs 10 secured in openings provided therefor in the stone bed, said bolts having their heads bearing upon flanged washers 11 which are fitted through openings provided therefor in the outer flanges of the track rails, as shown in Fig. 7. A firm secure level track upon which the machine may travel is thus provided.

The machine includes a truck which is adapted to run upon the rails 5 and said truck comprises side plates 12 the upper edges of which are arcuate and have secured thereon a roof plate 13, said roof plate extending to the ends or lower edges of the side plates, as will be understood upon reference to Fig. 3. At the corners of the truck are provided brackets 14 to the sides of which are secured plates 15 having narrow extensions 90 or tongues 16 projecting from their lower ends, and upon each tongue 16 is mounted a roller 17 which bears against a side of the adjacent track rail 5 so as to hold the truck to the track and prevent lateral oscillation or weaving. Immediately adjacent the corners of the truck, angle levers 18 are mounted upon the roof plate 13 with their lower arms projecting toward the track, as clearly shown in Fig. 6, and upon the free ends of said lower arms are mounted rollers 19 which bear against the undersides of the heads of the tracks, as clearly shown in Fig. 7, thereby holding the truck down to the track and preventing jumping of the track when the cutters are operating. To the bell cranks are pivoted links 20 which are connected at their inner ends by a turn buckle 21 so that, by adjusting the turn buckle, the rollers 19 may be brought into the proper engagement with the track rails to hold the truck thereto. If the turn buckle be manipulated to draw the links 105

20 together, the rollers will be released from the track rails and the truck may then be lifted therefrom.

While the arrangement just described, and shown particularly in Figs. 6 and 8, is preferred because of its friction-minimizing characteristics, a somewhat simpler and cheaper construction may be used and is shown in Fig. 9. A plate or bracket 76 is secured upon the roof plate 13 at 5 each corner of the same by bolt and slot connections, as indicated at 77, permitting the plate to be adjusted transversely of the track rail. At one side, the bracket 76 is formed with an offset at its lower end presenting a vertical shoulder 78 to the 10 side of the rail and a depending keeper plate 79 is secured to the opposite side of the bracket to bear against and slide along the opposite side of the rail so that weaving of the truck is prevented. A second slide or keeper plate 80 is 15 secured to the underside of the off-set and projects under the head of the rail to hold the truck 20 down to the rail.

It will be understood readily from an inspection of the drawings that the side plates 12 and the 25 roof plate 13 of the truck constitute a housing within which the operating mechanism is contained so that it will be protected from the weather elements as well as chance blows from falling tools or rocks and from the muck thrown 30 out by the rotating saws. Within the housing thus provided, at the corners of the same, are flanged rollers 22 which run upon the track rails 5 and thereby serve to transport the machine. The rollers are secured upon axles 23 at the ends 35 of the machine and upon each axle is secured a sprocket 24 about which is trained a sprocket chain 25 whereby, if either axle be rotated, the rotation will be imparted to the other axle so that they will both be rotated in the same direction 40 and at the same speed. The sprocket chain 25 is passed under idlers 26 within the housing, adjacent the ends thereof, so that there will be no interference between the chain and the saw arbor which will be presently referred to. Motion is 45 imparted to the axles 23, so that the machine will be propelled along the tracks, by a motor 27 disposed within the housing and connected with the adjacent axle by chain and sprocket gearing, indicated at 28. It will be noted that the motor 50 27 is carried by a frame 29 secured upon the roof plate 13 at one end of the housing and disposed above the adjacent axle 23, as shown most clearly in Fig. 3. The motor is a reversible variable speed electric motor and in itself constitutes no part of 55 the present invention. It may be procured from usual sources and is illustrated in a conventional manner only. Doors 30 are provided in the roof plate to give access to the working parts for inspection or repairing of the same and the several motor circuits are controlled by push button switches, located at 31, upon the roof plate where they may be conveniently manipulated. The circuits for the several motors are not illustrated inasmuch as they do not form a part of the invention, and the current for operating the motors 60 may be provided by storage batteries or may be furnished by a trolley system, as may be most convenient under any given circumstances. It is to be understood also that the usual water connections for cooling the saw blades are to be provided, and at 32 I have indicated a water pipe for cleaning the track rails as the machine travels thereover. It may be also noted that, as shown in 65 Fig. 6, the brackets 14 extend close to the upper 70 surfaces of the rails so that any debris which may lodge thereon will be pushed therefrom.

The saw arbor 33 extends transversely through the housing and projects beyond the two opposite sides of the same, saws 34 being carried by both ends of the saw arbor. Each saw consists of a circular blade or disk and inset teeth 35 of the usual form which are wider than the thickness of the disk and are preferably centered thereon. Each disk is fitted between hub plates 36 which are mounted upon the saw arbor, and spacing washers 37 are provided upon the arbor between adjacent hub plates and between the innermost hub plates and an abutment shoulder on the arbor so that the saws may be properly spaced, a nut 38 upon the end of the arbor serving, when turned home, to clamp all the saws and the washers firmly together and against the annular abutment shoulder 39 formed upon the arbor, as will be understood. By varying the number of spacing washers employed, the saws may be set at any desired distance apart according to the thickness desired in the stone block which is to be produced, and slabs of various widths may be cut simultaneously. The side plates 12 of the machine housing have openings formed therethrough and in these openings are fitted large disks 40, anti-friction bearings 41 being mounted in these disks eccentrically, as will be understood upon reference to Fig. 7. The saw arbor 33 is mounted 105 in the bearings 41 and in similar bearings provided in a bracket 42 which depends from a frame 43 which is secured to and extends between the disks 40, as shown in Figs. 3, 5 and 7. Upon the inner or upper side of the frame 43 is mounted 110 a variable speed reversible electric motor 44 the shaft 45 of which is connected by chain and sprocket gearing 46 with the saw arbor so that the saws may be driven by said motor. Flanges or rings 47 and 48 are rigidly secured to the inner 115 and outer faces of the disks 40, at the margins of the same, and project beyond the disks, as best shown in Fig. 7, whereby to engage the opposite faces of the side plates 12 and thereby retain the disks 40 in position in the side plates. The inner 120 ring or flange 47 is provided with gear teeth 49, on its outer periphery, so that said flange constitutes a gear which is engaged by a pinion 50 secured upon a shaft 51, near the end of the same, so that if said shaft be rotated the disks 40 will 125 be caused to turn about their own centers and, consequently, shift the saw arbor 33 and the saws to a higher or lower position. This will be readily understood upon reference to the dotted lines in 130 Fig. 3, and this operation permits the saws to be fed downwardly in the channels as the cutting of the stone proceeds. The shaft 51 is journaled, at its ends, in the side plates 12 and is connected by chain and sprocket gearing, indicated at 52, with a reversible variable speed electric motor 53 135 which is carried by a frame 54 secured upon the inner side of the roof plate 13, as shown clearly in Fig. 3. It will thus be seen that the travel of the machine from end to end of the quarry bed, the driving of the saws, and the adjustment of 140 the saws to follow up the work are accomplished by separate, independently controlled motors and the operation of the machine, therefore, will be easily controlled so that the saws may be accurately held to the work and the sides of the stone 145 cut in true planes. The saw arbor should, of course, clear the track rails when in its lowest position and to enable the cutters or saw blades to make a channel of maximum depth without interference between the arbor and the rails, an- 150

nular grooves 81 are formed in the arbor directly over the rails, as shown in Fig. 7. By thus reducing the diameter of the arbor to the limit of safety at these points, the saws are permitted to descend 5 until the hub plates are just out of contact with the quarry bed.

Generally, the weight of the machine will hold it to the rails so that the traction between the wheels or rollers 22 and the track rails will be 10 sufficient to effect the desired travel of the machine. It may be, at times, however, advantageous to provide a stabilizing device to maintain steadiness in the machine during travel thereof and for that purpose, winding drums 55 may be 15 mounted upon the axles 23. A cable 56 has one end secured to one end of the housing and extends therefrom longitudinally of the track to one bank of the quarry, indicated at 57, Fig. 4, where it is trained around an idler 58 mounted 20 upon said bank of the quarry. From said idler, the cable is carried back to the housing and passed through an opening 59 provided in the roof plate to be wrapped around the adjacent drum 55, as shown in Fig. 5. The cable is then passed 25 through the housing, below the saw arbor, to the opposite drum 55 around which it is in turn wound, then passed through a second opening 59 and out longitudinally of the quarry bed. From the second opening 59, the cable is carried to an 30 idler 60 mounted upon the opposite quarry bank 61 and thence back to the housing to which it is secured. As travel of the machine is effected, the cable will be caused to wind and unwind on the drums so that a pull will be exerted upon 35 the cable at one end of the housing, the cable at one side of the housing decreasing in relative length, and, at the other side, increasing in relative length while it is maintained taut at both sides by the drums. The travel of the apparatus 40 is thus rendered steady and smooth and oscillations which might develop otherwise are overcome.

It will be understood, from what has been said, taken in connection with the accompanying drawings, that the machine is caused to travel longitudinally of the tracks and the saws are simultaneously rotated so that they will form channels in the stone to the desired depth or the depth permitted by the radius of the saws. The 45 travel of the machine may be continuous, back and forth, and the saws adjusted to cut at a slightly greater depth on each trip. Inasmuch as the saws are working at both ends of the saw arbor and at both sides of the housing, cuts may 50 be made close to the wall or bank of the quarry and after the longitudinal cuts have been made and the saws withdrawn from the channels, the track may be set at a right angle to its previous 55 position and the machine then operated to cut across the previously formed channels so that the long slabs of stone will be divided into blocks of the desired lengths. As the saw arbor is mounted in the housing between the ends thereof, when the saws are working at both sides of 60 the machine, an upward thrust is imposed equally on the two side plates of the housing which is transmitted to the track-engaging elements at the corners of the truck so that the truck is balanced and effectually held against all oscillation or weaving. It will be understood, of course, 65 that, when the machine is set to make the transverse cuts, some of the saws may be removed and if so desired all of the saws at one end of the saw arbor may be removed so that the blocks may 70

be formed in any desired lengths. As the saws make clean smooth cuts and a plurality of longitudinal channels are simultaneously made, the slabs of stone will be dressed on two opposite faces at each operation of the machine and inasmuch as the machine is held positively to a rectilinear path, the channels will be formed on straight lines. The provision of several independently operating motors furnishes perfect control of the machine so that the saws will act upon the stone to produce true faces and subsequent dressing of the stone will be obviated almost entirely. The progress of the saws through the rock bed will not be forced to such an extent as may produce excessive heating and possible explosion of the blades, inasmuch as when the saws encounter an obstruction the rollers 22 may slip upon the rails until the obstruction has been overcome. When the slabs are cut transversely so as to be divided into blocks of desired lengths, the blocks or slabs will be produced at the quarry with the two opposite sides and the two ends dressed. By the use of this machine, a slab or block having four finished faces is produced at the quarry and the waste and expense of transporting rough blocks and subsequently dressing them to the desired dimensions is eliminated. Of course, special designs of detailed carving must be produced later but where the work is rectangular blocks practically ready to be set may 105 be furnished direct from the quarry more speedily and at less expense than by the methods heretofore generally followed.

Having thus described the invention, I claim:

1. In a stone-channeling machine, a housing 110 comprising side plates having circular openings therein, disks rotatably fitted in and filling said openings, a saw arbor mounted eccentrically through said disks, saws carried by said arbor, a motor supported by and between the disks and 115 operatively connected with the saw arbor for rotating the same, and means carried by and between the side plates for rotating the disks whereby to effect vertical adjustment of the saw arbor and the saws thereon.

2. A stone-channeling machine comprising a truck having side plates provided with circular openings therethrough, disks filling and rotatable in said openings, a frame secured to and extending between said disks, a saw arbor journaled eccentrically in the disks and extending beyond the side plates of the truck, a motor mounted on said frame and operatively connected with the saw arbor for rotating the latter, and means carried by and between the side plates for rotating 125 the disks to vertically adjust the saw arbor.

3. A stone-channeling apparatus comprising a truck including side plates having openings therein, disks rotatably fitted in the openings in the side plates, flanges secured to the opposite sides 130 of the disks and engaging the opposite faces of the side plates, the inner flange having gear teeth on its outer periphery, a saw arbor journaled in the disks, a motor carried by the disks and geared to the saw arbor, a transverse shaft mounted in 135 and extending between the side plates of the truck, gears on said shaft meshing with the gear teeth on said inner flange, and a motor mounted on the truck and geared to said transverse shaft.

4. A stone-channeling machine comprising a 140 truck consisting of side plates having arcuate upper edges and a roof secured on and co-terminous with the upper edges of the side plates, the side plates having circular openings therethrough, disks rotatably fitted in the openings in 145

the side plates, a saw arbor eccentrically mounted in said disks, saws on the arbor at the outer sides of the disks, a motor supported by and between the disks and operatively connected with the saw arbor to rotate the same, a motor mounted on the roof and operatively connected to the disks to rotate the same and effect vertical ad-

justment of the saw arbor, track-engaging rollers mounted within the truck adjacent the corners of the side plates, and a motor mounted on the roof and operatively connected with said rollers to rotate the same and propel the truck. 80
